UNITED STATES PATENT OFFICE

JOHN CHRISTIE, OF SUNDERLAND, ENGLAND, ASSIGNOR TO A. REYROLLE & COMPANY LIMITED, OF HEBBURN-ON-TYNE, ENGLAND, A COMPANY OF GREAT BRITAIN

ELECTRIC SWITCH GEAR

Application filed January 15, 1931, Serial No. 508,988, and in Great Britain February 21, 1930.

This invention relates to electric switch-gear of the metal-clad type and more particularly to switchgear such as is necessary for dealing with heavy loads on high voltage systems.

In such switchgear it is essential to provide for the isolation and removal of the circuit-breakers from the rest of the apparatus and in many known forms the removal can only be accomplished by lowering the circuit-breaker and its tank. This necessitates suspending the circuit-breaker from some kind of framework and the provision of raising and lowering gear. It also means that considerable vertical space is occupied by the gear. The suspension of large and heavy circuit-breakers is undesirable but if not suspended the removal of the circuit-breaker in most constructions is difficult without interfering with the busbar or other fixed connections to the switchgear.

The primary object of the present invention is the construction of a metal-clad switchgear in which although the circuit-breaker need not be lowered, at any rate to any great extent, and thus its tank may rest say upon the ground, it can be isolated and removed without interference with the busbars.

This is accomplished according to the invention by the provision of a tubular casing which passes through the busbar chamber and is detachably connected round an orifice in the tank or chamber containing the circuit-breaker. In this tubular casing is an insulated conductor normally connecting, preferably through an isolating switch, the busbar and one of the fixed contacts of the circuit-breaker, such insulated conductor being withdrawable through the top of the tubular casing.

The lower end of the tubular casing may be in the form of a flexible extension or sleeve, say of corrugated metal, making a flanged joint round the orifice in the top plate of the circuit-breaker tank so that it can be readily detached and displaced sufficiently to allow the tank to be moved more or less horizontally after the insulated conductor has been withdrawn. This flexible sleeve may

normally be extended when it is connected to the tank so that it draws itself clear when the joint is broken.

The tubular casing is of insulating material, for instance porcelain, and may be made as a condenser-insulator. It passes through the busbar chamber, usually oil-filled, and is secured therein in any convenient way. At some convenient place inside the busbar chamber the tubular casing is provided with a metal contact ring which can be connected through a switch in the busbar chamber to the busbar. This switch serves when open to isolate the tubular casing and preferably a second position of the switch earths it. The inside of the contact ring makes connection with spring or other frictional contacts at the upper end of the insulated conductor, which conductor passes right down through the tubular casing and through a hollow insulator fixed in the top of the circuit-breaker tank, and its lower end makes a plug and socket or like connection at the bottom of the hollow insulator.

At the top of the tubular casing is a cover normally closed but which when removed affords access to the insulated conductor which can then be withdrawn wholly or partially.

The accompanying drawing is a vertical section illustrating diagrammatically one construction of switchgear according to this invention.

In this figure, A is the circuit-breaker tank and B and C are respectively the busbar and feeder or cable chambers supported in any convenient way independently of the circuit-breaker tank A which is shown as resting on a truck D almost at ground level.

Passing through each of the chambers B and C is a tubular casing E having at its lower end a flexible sleeve or extension E¹ with a flange E² which can be bolted round an orifice in a plate A¹ forming part of the top cover of the tank A.

The tubular casing E in the example illustrated consists of two tubes of insulating material joined by a metal contact ring E³ and fixed top and bottom by flanged joints to the busbar chamber B or cable chamber C through which it passes.

In the tubular casing E is a conductor F surrounded by an insulating bushing F¹ which may be of the condenser type. About midway of its length where it passes through the orifice in the plate A¹, this insulating bushing is provided with a flanged collar or earthing plate F² which has a seating on the rim of the orifice. A divided or halved ring or washer G is placed above this flanged earthing plate F² and is clamped down by the flanged ring E² at the bottom of the flexible sleeve E¹.

The top end of the insulated conductor F has springy contacts F³ which make connection with the inside of the contact ring E³ in the tubular casing E, and the bottom end of the conductor F makes a plug and socket connection with one of the fixed contacts H of the circuit-breaker at the lower extremity of a hollow insulator H¹ which surrounds the insulated conductor F in the circuit-breaker tank A.

To the outside of the metal contact ring E³ is pivoted a switch arm J which can be moved by link mechanism J¹ into two positions. The switch J in the left-hand or busbar chamber B is shown in full lines in the position in which it connects the contact ring E³ to the busbar B¹ in the chamber. In the position indicated in broken lines, the ring E³ is joined to a contact B² on the wall of the chamber and consequently earthed.

The switch J in the feeder or cable chamber C is shown in full lines in its earthing position and in broken lines in the position in which it makes connection to the cable end C¹.

In the normal working position of the switch gear the insulated conductors F will each be in their lowermost positions, i. e. the position corresponding to that shown on the busbar side of the figure, and after the main circuit-breaker has been opened it can be isolated and earthed by the switches J. If mere inspection of the circuit-breaker is required, this can be done as usual in large switchgear by removing a cover from a man-hole (not shown) in the top plate of the tank.

If removal of the circuit-breaker is necessary for repair or replacement, the switches J are earthed and the flanged rings E² at the bottom ends of the flexible sleeves E¹ are unfastened from round the orifices in the plates A¹. The halved rings or washers G are then removed, thus leaving the conductors F and their bushings F¹ free. By removing the top covers E⁴ from the tubular casings E access is given to the insulated conductors F which can be withdrawn by inserting a suitable tool. In the figure the conductor F on the right-hand side is shown thus withdrawn.

When both conductors have been withdrawn it is possible to remove the circuit-breaker and its tank horizontally. For example, in the construction illustrated it can

be wheeled away on the truck D from under the rest of the gear.

It will be understood that there will be some easily removable form of coupling in the operating mechanism for the circuit-breaker, so that it can be uncoupled when the removal of the circuit-breaker and its tank is necessary.

It will be appreciated that the tubular casing constitutes a conduit or passage through the busbar or other chamber, and that the opening of the casing and withdrawal of the insulated conductor do not necessitate the withdrawal of the oil from the busbar or other chamber. The tubular casing itself may be oil-filled and in such a case a drain cock L may be fitted to the flexible sleeve E¹ so that the oil may be drained off before the joint between the sleeve and the top plate of the circuit-breaker is broken.

What I claim as my invention and desire to secure by Letters Patent is:—

1. In metal-clad electric switchgear, the combination of a circuit-breaker, a tank containing the circuit-breaker, a conductor of the circuit controlled by the circuit-breaker, a lead-in chamber for such conductor, a tubular casing passing through the lead-in chamber in such a manner as to form a separate compartment therein, means for detachably connecting such casing to the circuit-breaker tank round an orifice therein, and an insulated conductor so mounted within the tubular casing that it can be moved longitudinally therein to project into the circuit-breaker tank and constitute part of the connection from the main conductor to the circuit-breaker or can be withdrawn from the tank through the top of the tubular casing.

2. In metal-clad oil-immersed electric switchgear, the combination of a circuit-breaker, an oil-filled tank containing the circuit-breaker, a conductor of the circuit controlled by the circuit-breaker, an oil-filled lead-in chamber for such conductor, a tubular casing passing through the lead-in chamber and constituting a separate oil-filled compartment therein, means for detachably connecting such casing to the circuit-breaker tank round an orifice therein, an isolating switch in the lead-in chamber, and an insulated conductor within the tubular casing normally projecting into the circuit-breaker tank and forming part of a connection from the circuit-breaker through the isolating switch to the main conductor, such insulated conductor being withdrawable through the top of the tubular casing.

3. In metal-clad electric switchgear, the combination of a circuit-breaker, a tank containing the circuit-breaker, a conductor of the circuit controlled by the circuit-breaker, a lead-in chamber for such conductor, a tubular casing passing through the lead-in chamber, a flexible extension of such casing by

- means of which it can be detachably connected to the circuit-breaker tank round an orifice therein, and an insulated conductor within the tubular casing which normally forms part of the connection from the main conductor to the circuit-breaker and is withdrawable through the top of the tubular casing, the arrangement being such that after disconnecting the flexible extension from the circuit-breaker tank and withdrawing the insulated conductor the circuit-breaker and its tank can be moved without interference with the rest of the gear and without lowering it to any great extent. 10
- 15 4. In metal-clad electric switchgear, the combination of a circuit-breaker, a tank containing the circuit-breaker, a conductor of the circuit controlled by the circuit-breaker, a lead-in chamber for such conductor, a tubular casing of insulating material passing through the lead-in chamber, means for detachably connecting such casing to the circuit-breaker tank round an orifice therein, an insulated conductor within the tubular casing which is normally connected at its lower end to the circuit-breaker and is withdrawable through the top of the tubular casing, a metal contact ring on the tubular casing, means for connecting the upper end of the insulated conductor to the metal contact ring, and means for connecting the metal contact ring to the isolating switch whereby the circuit-breaker can be connected either to the main conductor or to the earthed contact in accordance with the position of the isolating switch. 20
- 25 5. In metal-clad oil-immersed electric switchgear, the combination of a circuit-breaker, an oil-filled tank containing the circuit-breaker, a conductor of the circuit controlled by the circuit-breaker, an oil-filled lead-in chamber for such conductor, a tubular casing of insulating material passing through the lead-in chamber, a flexible extension of such casing by means of which it can be connected to the circuit-breaker tank round an orifice therein, an insulated conductor within the tubular casing which is normally connected at its lower end to the circuit-breaker and is withdrawable through the top of the tubular casing, a metal contact ring on the tubular casing, means for connecting the upper end of the insulated conductor to the metal contact ring, and means external to the tubular casing for connecting the metal contact ring to the main conductor in the lead-in chamber. 30
- 35 6. In metal-clad electric switchgear, the combination of a circuit-breaker, a tank containing the circuit-breaker, a conductor of the circuit controlled by the circuit-breaker, a lead-in chamber for such conductor, a tubular casing of insulating material passing through the lead-in chamber, a flexible extension of such casing by means of which it can be connected to the circuit-breaker tank round an orifice therein, an insulated conductor within the tubular casing which is normally connected at its lower end to the circuit-breaker and is withdrawable through the top of the tubular casing, a metal contact ring on the tubular casing, means for connecting the upper end of the insulated conductor to the metal contact ring, and means external to the tubular casing for connecting the contact ring to the main conductor in the lead-in chamber, the arrangement being such that after disconnecting the flexible extension from the circuit-breaker tank and withdrawing the insulated conductor the circuit-breaker and its tank can be moved without interference with the rest of the gear and without lowering it to any great extent. 40
- 45 7. In metal-clad electric switchgear, the combination of a circuit-breaker, a tank containing the circuit-breaker, two main conductors to be connected together through the circuit-breaker, a lead-in chamber for each main conductor, two tubular casings passing respectively through the two lead-in chambers, means for detachably connecting such tubular casings to the circuit-breaker tank round orifices therein, and an insulated conductor so mounted within each tubular casing as to be withdrawable through the top thereof, the two insulated conductors respectively constituting part of the connections from the circuit-breaker to the two main conductors. 50
- 55 8. In metal-clad electric switchgear, the combination of a busbar, an electric apparatus to be connected to the busbar, a tank containing such apparatus, a lead-in chamber for the busbar, a tubular casing passing through the busbar chamber in such a manner as to form a separate compartment therein, means for detachably connecting the tubular casing to the apparatus tank around an orifice therein, and an insulated conductor within the tubular casing normally projecting into the apparatus tank and forming part of a connection between the apparatus and the busbar, such insulated conductor being withdrawable through the top of the tubular casing. 60
- 65 9. In metal-clad electric switchgear, the combination of a busbar, an electric apparatus to be connected to the busbar, a tank containing such apparatus, a lead-in chamber for the busbar, a tubular casing passing through the busbar chamber in such a manner as to form a separate compartment therein, a flexible extension of such tubular casing by means of which it can be detachably connected to the apparatus tank around an orifice therein, and an insulated conductor withdrawably mounted within the tubular casing. 70
- 75 10 110 115 120 125 130

and normally forming part of a connection between the apparatus and the busbar.

10. In metal-clad electric switchgear, the combination of a busbar, an electric apparatus to be connected to the busbar, a tank within which such apparatus is immersed in oil, an oil-filled lead-in chamber for the busbar, a tubular casing of insulating material so mounted within the busbar chamber as to constitute a separate oil-filled compartment therein, means for detachably connecting the tubular casing to the apparatus tank around an orifice therein, a metal contact member on the tubular casing, means external to the tubular casing for connecting such member to the busbar within the lead-in chamber, and an insulated conductor so mounted within the tubular casing that it can be moved longitudinally therein to project into the apparatus tank and connect the apparatus to the metal contact member or can be withdrawn from the apparatus tank to break such connection.

25 In testimony whereof I have signed my name to this specification.

JOHN CHRISTIE.
